UNITED STATES PATENT OFFICE.

CHARLES R. CARPENTER, OF SAN DIEGO, CALIFORNIA.

ROTARY EXPLOSIVE-ENGINE.

1,177,380.

Specification of Letters Patent. Patented Mar. 28, 1916.

Application filed April 27, 1915. Serial No. 24,371.

To all whom it may concern:

Be it known that I, CHARLES R. CARPENTER, citizen of the United States, residing at San Diego, in the county of San Diego and State of California, have invented certain new and useful Improvements in Rotary Explosive-Engines, of which the following is a specification.

My invention relates to rotary internal explosive engines having twin cylinders firing at intervals, thus producing impulses to a common shaft at different points and having no dead center.

The object in view is to produce laterally moving fluid pressure operated gates utilizing the exhaust gases to operate the gates in one direction and a common fluid pressure supply to operate the gates in the other direction.

Another object is to minimize the cost by simplicity of construction and produce increased efficiency by utilizing the expansive power in the exhaust that is ordinarily lost, to operate the gates.

A further object is to impart to the rotor an impulse through the greatest possible proportion of its rotation, by the prompt movement of the gates, said movement being produced by energy ordinarily lost and by use

of said power for movement to the gates, the rotor is relieved of said duty and increased efficiency is attained.

These and other objects in view will appear in the description and be particularly pointed out in the claims.

Referring to the drawings, Figure 1 is a plan view of my improved engine showing the fluid pressure tank in elevation and the fuel generator in section. Fig. 2 is a vertical longitudinal section of the engine, taken on the line of the main or power shaft. Fig. 3 is a vertical transverse section taken centrally through one of the rotor casings, showing the rotor and the gate in section with the near portion of the casing removed, showing the attaching flange of the adjoining portion in elevation. Fig. 4 is a vertical transverse section showing one of the rotor casings in elevation and its exhaust chamber in section showing its communication with the gate casing, and also showing the fuel inlet ports. Fig. 5 is a similar view to more fully illustrate the slide valve for fuel control with the gate casing in section. Fig. 6

is a detail view of the slide valve casing, 55 and, Fig. 7 is a detail view of the slide valve.

Similar numerals indicate corresponding parts in all the figures of the drawings, in which—

1 is the bed plate, preferably of cast metal 60 and for convenience in construction, said bed plate is formed in three parts each provided with attaching flanges 2 extending up from the face of the bed plate, said flanges being provided with recesses 3 in which rest, when 65 the parts are assembled, the attaching flanges 4 of the rotor casings 5, said rotor casings being formed in two sections as is the usual practice in devices of this character, each section carrying a lining integral 70 housings 6, provided with any preferred form of oiling means such as oil cups 7 adapted to supply a lubricant to the shaft 8 mounted for rotary movement in the housings. 75

As will be seen in Fig. 2, the inner casing sections have cast or formed integral therewith directly beneath the housings, a portion of the gate casing, as shown at 9, said portion being provided with attaching flanges 80 10, to which the central portion 11 of the gate casing which is also provided with attaching flanges is secured.

By this construction, it will be seen that the parts are conveniently cast and machined 85 and finally assembled with all the parts firmly bolted together and being securely bolted down, as shown at 12, the device will possess the firm and rigid construction otherwise formed only when the casings are 90 cast in one piece, yet possessing all the conveniences incident to a construction where the parts are accessible, convenient for shipment, as well as for prompt replacement.

Mounted rigidly on the shaft within the 95 casings are rotors having the central disk portion 13 mounted on the shaft, the head 14 projecting from the disk portion and adapted to have a snug working fit within the circular portion of the casing, said head portion acting as the piston within the casing or annular cylindrical portion thereof and is adapted to be forced by the explosion to traverse said cylindrical portion and impart power to the shaft, said heads 14 being provided with packing rings (not shown) if found expedient. 100 105

As clearly shown in Fig. 4, the inner sec-

tions of the rotor casings are provided with exhaust passages 15 formed in an offset cast portion of the casing lying parallel with and adjacent to the cylindrical portion 5 thereof, said offset portion having the adjacent outer section 9 of the gate casing formed integral therewith, the exhaust passage being in open communication with the gate casing. An exhaust port 16 is provided 10 for the passage of the exhaust gases from the annular cylindrical portion of the casing to the passage 15. The gate casing, as shown in Fig. 2, is in this case shown cylindrical in cross section and has slidably mounted 15 therein for lateral movement, the gates, there being sufficient distance between the inner ends of the gate members to provide a fluid pressure chamber 17, which is at all times in open communication with the fluid 20 pressure tank 18, through pipe 19 (Fig. 1), said pipe 19 being provided at 20 with a pressure indicator adapted to maintain a pressure of approximately twenty pounds in the pressure chamber.

25 The gates 21 consist of the vertically disposed plate portion 22, adapted to be advanced with the plate portion 22 resting in grooves 23 formed in the casing across the cylindrical portion of the casing, entirely 30 closing same.

The plate 22 is solid for a width equal to the cross section of the bore of the casing and is provided with a port or passage 24 through which the exhaust gases delivered 35 through the exhaust passage 15 may pass and act upon the entire surface of the disk portion 25 of the gate to force the plate portion 22 back out of its position across the casing. A disk 26 having, as does the disk 40 25, a sliding fit within the gate casing, is spaced by post 27 from disk 25 a distance approximately that of the throw of the gate and is adapted to be acted on to give the gate its forward movement by fluid pressure in chamber 17, the end walls of said 45 chamber 17 being formed by the disks 26 and against which a constant pressure is maintained.

Exhaust ports 28 are provided in the gate 50 casing in such a position in relation to the throw of the gates as to provide means of exit for the exhaust gases, when the gate is retracted, said port leading into the exhaust manifold 28^a, the disk 25 in its movement 55 passing beyond the port 28 to allow the exhaust gases to escape, but when the gate is forward, as shown in the position to the right of Fig. 2, it will be seen that disk 26 never advances beyond said port 28 and 60 therefore prevents the escape of pressure maintained in chamber 17.

To insure proper timing in the operation 65 of the gate under varying conditions of load, spring pressed triggers 29 are provided to automatically engage near plate 22, the

edge of rings 25 in their retracted position, maintaining them in said position and from which they are released by tripping fingers 30 mounted on adjustable annular rings 31 secured to the shaft 8, said annular rings 70 also carrying brushes 32 for closing the circuit and producing the firing spark.

Oil cups 33 are provided for the lubrication of the gates and packing rings (not shown) may be provided in the disk members 25 and 26 of the gates to prevent leakage if found necessary.

By reference to Figs. 3, 4 and 5, it will be seen that the disk portion 13 of the rotor is cut away at 34, said cut-away portion 80 forming a passage through which the fuel reaches the explosion chamber from a series of inlet ports 35 in the casing. Ports 35 are controlled from within the casing by the disk portion of the rotor which normally closes the ports except when cut-away portion 34 passes beneath them.

Fuel is supplied to a valve casing 36 through pipe 42 and port 43. A valve 37 having a hollow portion 38, a solid portion 39 and an operating arm 40 extending through slot 41 in the valve casing, is adapted to be adjusted within the valve casing to permit fuel entering the valve casing through port 43 to pass along through the 95 hollow portion 38 of the valve and through more or less of the inlet ports 35 into the explosion chamber. By the adjustment of slide valve 37 to bring portion 39 thereof over more or less of the ports 35, the quantity of fuel admitted to the casing is controlled. At each revolution of the rotor in the direction indicated by the arrow, when the cut-away portion 34 of the rotor passes beneath the inlet ports 35 in the casing, the 100 port or ports not covered by the portion 39 of the valve form a direct communication from pipe 42 through port 43, hollow portion 38 of the valve, through said port or ports and cut-away portion to the explosion 105 chamber.

The lever 40 is secured to a rotary frame 44 made up of connected bands encircling the inner housing 6 of the casing, said frame being adjustable in a rotary manner on the 115 housing by the lever 45 secured to the outer end of the arm 46 which extends from the frame 44.

Mounted on the rotatably adjustable frame 44 are contact points in the electric 120 ignition circuit in such a position as to form a gap in said circuit, but so arranged that the brush 32 carried by the ring 31 will at the proper time in the rotation of the shaft 8, close said gap and complete the circuit 125 to form a spark for ignition at the spark plug shown at 46.

The circuit closure or contact points, as above noted, are mounted on the adjustable frame 44 and are therefore moved in such a 130

manner as to advance or retard the spark simultaneously with the control of fuel intake.

By reference to Fig. 1, the fuel generator 5 47 supplies the fluid explosive mixture through pipe 48, said pipe being provided with a governor 49 to electrically control the supply of fuel.

A shaft 50 mounted on the engine base 10 parallel with the main shaft, is driven by chain 51, operating over sprocket wheel 52 on the main shaft and sprocket wheel 53 on shaft 50, said shaft 50 being utilized as a common power shaft for the water pump 15 54 to circulate through piping 55 a cooling medium for the rotor casings, said shaft also operating the magneto 56, and an air compressor 57, the latter through pipe 58 leading to tank 18 maintaining the desired pressure 20 therein. Any other preferred means may be employed to transfer power to shaft 50.

The operation which appears to be obvious is in part as follows: The fuel is admitted 25 through one or more of the ports 35 to the explosion chamber 59, said chamber being formed between the rotor head 14 and the portion 22 of the gate, which at that time rests across the casing entirely closing all 30 communication with the chamber beyond said gate and producing a stationary backing against which the expansion in the fuel due to the explosion may take effect in forcing the rotor head around the casing. The 35 gate remains in the position above referred to until the edge of the rotor head passes the exhaust port 16. By this construction, the gases are expanded until their pressure is only sufficient to operate the abutment, there- 40 by utilizing their energy to the fullest extent possible. When port 16 is uncovered by the rotor head, the exhaust gases will at once pass out through passage 15, into gate chamber and into contact with the disk 25 45 of the gate, forcing same back and with it the portion 22 clear of the chamber and allow the head 14 to pass. At the extreme rearward position of the gate, exhaust port 28 is passed by disk 25, thus opening a pas- 50 sage for the exhaust out to the exhaust manifold. The trip finger 30 is so positioned that trigger 29 which has caught and held the gate in its rearmost position, will be lifted to release the gate immediately after 55 the head 14 passes, when the pressure maintained at all times in chamber 17 will in contact with disk 26, force the gate back into its initial position.

A single port may be used in place of 60 ports 35, the slide valve 37 covering more or less of said port when adjusted. also other minor changes may be resorted to without departing from the spirit of the invention.

65 The exhaust of chamber 5 takes place

while the gases are still under sufficient pressure to operate the gate against the fluid pressure in chamber 17, and upon its release through port 28, the outward rush or inertia of said gases, backed up by the forward movement of the rotor head from the point at which exhaust port 16 is uncovered, to the point at which it passes the abutment, not only relieves the pressure in the casing but rarefies the pressure in the 75 casing to such an extent that sufficient pressure is not established within the casing in advance of the rotor head on its next rotation, to overcome the fluid pressure in chamber 17 and move the abutment from its forward position. 80

With the proper timing of trip 29 to release disk 25 and cover exhaust port 28 immediately after exhaust gases are allowed to escape, a partial vacuum will be set up in 85 the casing in advance of the head 14, and while this partial vacuum may be slowly dispelled in the event the engine ceases to rotate, it will be maintained a sufficient length of time when the engine is running. 90

What I claim as new and desire to secure by Letters Patent is:—

1. In a rotary motor, the combination of twin annular chambers, rotors movable in said chambers and connected to a concentric 95 rotating shaft, gates movable to and from a position across the chambers, a series of inlet ports for fuel gas covered and uncovered by the rotors, valves controlling admission of gas to the inlet ports, means for forcing the gates in one direction and means whereby the exhaust gases force the gates in the other direction. 100

2. In a rotary motor, the combination of twin annular chambers, rotors movable in 105 said chambers and connected to a concentric rotating shaft, gates movable to and from a position across the chambers, a series of inlet ports for fuel gas covered and uncovered by the rotors, valves controlling admission of 110 gas to the inlet ports, fluid pressure means for forcing the gates in one direction and means whereby the exhaust gases force the gates in the other direction.

3. In a rotary motor, the combination of twin annular chambers, rotors movable in 115 said chambers and connected to a concentric rotating shaft, gates movable to and from a position across the chambers, a series of inlet ports for fuel gas covered and uncovered by the rotors, valves controlling admission of gas to the inlet ports, means to admit fluid pressure between the gates to force them across the chambers and means whereby the exhaust gases retract the gates. 120

4. In a rotary motor, the combination of twin annular chambers, rotors movable in 125 said chambers and connected to a concentric rotating shaft, gates movable to and from a position across the chambers, a series of 130

- inlet ports for fuel gas covered and uncovered by the rotors, valves controlling admission of gas to the inlet ports, means to admit fluid pressure between the gates to admit said gates across the chambers alternately and means whereby the exhaust gases of each chamber retract the gate operating therein.
5. In a rotary motor, the combination of 10 twin annular chambers, rotors movable in said chambers and connected to a concentric rotary shaft, gates movable to and from position across said annular chambers, explosion chambers adjacent said gates, valve controlled ports communicating with said annular chambers on one side of the gates, and means carried by the rotors within the annular chambers for opening and closing communication between the ports and the 15 explosion chambers.
6. In a rotary motor, the combination of 20 twin annular chambers, rotors movable in said chambers and connected to a concentric rotary shaft, gates movable to and from position across said annular chambers, explosion chambers adjacent said gates, a series of fuel inlet ports, slide valves adapted to close more or less of the ports, and means for opening and closing communication 25 between the ports and the explosion chambers.
7. In a rotary motor, the combination of 30 twin annular chambers, rotors movable in said chambers and connected to a concentric rotary shaft, gates movable to and from position across said annular chambers, explosion chambers adjacent said gates, a series of fuel inlet ports, slide valves adapted to close more or less of the ports, and means carried by the rotors within the 35 annular chambers opening and closing communication between the ports and the explosion chambers.
8. In a rotary motor, the combination of 40 twin annular chambers, rotors having central disk portions and head portions movable in the chambers and connected to a concentric rotary shaft, gates movable to and from position across the annular chambers, explosion chambers between said head portion of the rotors and the gates when across the annular chambers, fuel inlet ports communicating with the explosion chambers, the inlet ports being closed by the disk portions of the rotors during part of their 45 rotation.
9. In a rotary motor, the combination of 50 twin annular chambers, rotors having central disk portions and head portions movable in the chambers and connected to a concentric rotary shaft, gates slidably in opposite directions within a casing between the annular chambers, fluid pressure admitted to the casing between the gates to advance 55 the gates across the annular chambers and 60 form explosion chambers between said gates and said head portion of the rotors, and means for admitting fuel gas to the explosion chambers.
10. In a rotary motor, the combination of 65 twin annular chambers, rotors having central disk portions and head portions movable in the chambers and connected to a concentric rotary shaft, gates slidably laterally within a casing between the annular chambers beneath the rotary shaft, means between the gates to advance them alternately 70 in opposite directions across the annular chambers, explosion chambers formed in the annular chambers between the head portions of the rotors and the gates, fuel inlet ports 75 communicating with the explosion chambers, and means within the annular chambers to open the inlet ports during part of the rotation of the rotors.
11. In a rotary motor, the combination of 80 twin annular chambers, rotors movable in said chambers and connected to a concentric rotary shaft, gates slidably mounted in a casing between the annular chambers for alternate opposite movement across the 85 chambers, a common means for advancing the gates in opposite directions, explosion chambers formed in the annular chambers between the rotors and the gates, fuel inlet ports 90 communicating with the explosion chambers, and means for retracting the gates by pressure in excess of the advancing means.
12. In a rotary motor, the combination of 95 twin annular chambers, rotors movable in said chambers and connected to a concentric rotary shaft, gates slidably mounted in a casing between the annular chambers for alternate opposite movement across the 100 chambers, a common means for advancing the gates in opposite directions, explosion chambers formed in the annular chambers between the rotors and the gates, fuel inlet 105 ports communicating with the explosion chambers, and means for retracting the gates by the exhaust gases.
13. In a rotary motor, the combination of 110 twin annular chambers, rotors movable in said chambers and connected to a concentric rotary shaft, gates slidably mounted in a casing between the annular chambers for alternate opposite movement across the 115 chambers, a common means for advancing the gates in opposite directions, explosion chambers formed in the annular chambers between the rotors and the gates, fuel inlet 120 ports communicating with the explosion chambers, and exhaust passages connecting the exhaust ports and the gate casing for 125 retracting the gates.
14. In a rotary motor, the combination of 125 twin annular chambers, rotors movable in said chambers and connected to a concentric rotary shaft, gates slidably mounted in a 130

casing between the annular chambers for alternate opposite movement across the chambers, a common means for advancing the gates in opposite directions, explosion 5 chambers formed in the annular chambers between the rotors and the gates, fuel inlet ports communicating with the explosion chambers, exhaust ports in the annular casings, and exhaust passages connecting the exhaust ports and the gate casings to admit 10 the exhaust gases into the casing and retract the gates.

In testimony whereof I affix my signature.

CHARLES R. CARPENTER.
